(57) **CLAIM**

The ornamental design for a spill resistant lid, as shown and described.

DESCRIPTION

FIG. 1 is a front perspective view of the spill resistant lid and bowl.

FIG. 2 is a rear perspective view of the spill resistant lid and bowl; and,

FIG. 3 is a side view of the spill resistant lid and bowl.

The bowl is shown in the drawings in broken lines as an illustration of an environmental structure, and forms no part of the claimed design.
